UNITED STATES PATENT OFFICE.

MORRIS B. DRAPER, OF GRAND RAPIDS, MICHIGAN.

DESIGN FOR A THROAT-BAND.

SPECIFICATION forming part of Design No. 35,496, dated December 31, 1901.

Application filed October 28, 1901. Serial No. 80,347. Term of patent 3½ years.

To all whom it may concern:

Be it known that I, MORRIS B. DRAPER, a citizen of the United States, residing at the city of Grand Rapids, in the county of Kent and 5 State of Michigan, have invented and produced a new and original Design for a Throat-Band for Medicinal Purposes, of which the following is a specification.

My invention relates to a new and original 10 design for throat-bands, and is illustrated in the accompanying drawings, wherein—

Figure 1 shows a perspective view of the throat-band constructed in accordance with my design. Fig. 2 shows a sectional view 15 thereof.

The leading feature of my design consists of a throat-band formed of a single piece of material having sides A of convexo-concave

curvature transversely and which terminate in a thickened portion D, which depends below the sides A, as at E, and is of convexo-convex curvature longitudinally.

The design presents a throat-band of novel and distinguishing appearance.

Having thus described my invention, what I claim is—

The design for a throat-band herein shown and described.

In testimony whereof I have hereunto set my hand in presence of two subscribing witnesses.

MORRIS B. DRAPER.

Witnesses:

ARTHUR C. DENISON,
EDWARD TAGGART.
